TERMINAL MOUNTING

Filed Aug. 7, 1937

FIG. 1

UNITED STATES PATENT OFFICE

2,152,379

TERMINAL MOUNTING

Lealdas W. Haig, Warren, Ohio, assignor to The Standard Transformer Company, Warren, Ohio, a corporation of Ohio

Application August 7, 1937, Serial No. 157,945

4 Claims. (Cl. 174—151)

This invention relates to improvements in terminal mountings, particularly mountings for bus bars used as terminals of a transformer. The application of the invention is not necessarily confined to that purpose, however.

One of the objects of the invention is the provision of a mounting of this character, of relatively simple low cost construction, so designed as to permit expansion and contraction of the terminal without damage to the insulation employed.

Another object is the provision of a mounting which shall be oiltight, watertight, and of generally weatherproof construction.

15. A further object is the provision of a mounting which shall be yieldable to some extent in order to absorb without damage blows or mechanical shocks of various kinds.

Other objects and features of novelty will appear as I proceed with the description of that embodiment of the invention which, for the purposes of the present application, I have illustrated in the accompanying drawing, in which—

Fig. 1 is a plan view of a fragment of a transformer cover upon which my mounting is employed;

Fig. 2 is an elevational view, partly in vertical section, of the construction of Fig. 1; and

Fig. 3 is a cross-sectional view, taken substantially on the line 3—3 of Fig. 2, certain parts being broken away in order to more fully disclose the invention.

In the drawing, a fragment of the cover or other casing member of an electric transformer is illustrated at 10. An opening 11 is formed in the casing 10 to accommodate the terminal. In the present instance, the opening is of rectangular shape, but it will be understood that it is made to conform substantially with the cross-sectional shape of the terminal, whatever that may be. As here illustrated, the terminal comprises two bus bars 12 and 13 that are secured upon opposite sides of an intermediate strap 14 which may be an extremity of the secondary of the transformer. The strap 14 and the bus bars 12 and 13 are preferably fastened together by rivets 15 and also by welds 16 and 17, in order to effect a good electrical as well as a good mechanical union. The parts 12, 13, and 14, comprising the terminal, are ordinarily made of copper. Their combined cross-sectional area is less than the area of the opening 11, so that when the terminal is properly centered in the opening it is everywhere spaced from the sides of the opening, and there

is no electrical contact between the terminal and the casing.

At a point spaced outwardly from the casing 10, as illustrated in Fig. 2, I fit a metallic cap 18 onto the terminal. This cap, which is made of some non-ferrous, non-magnetic material, such as gun metal or other bronze, closely and tightly embraces the terminal and is joined thereto by a weld 19. The connection between the terminal and the cap 18 is therefore quite rigid.

Just beneath, or inwardly of, the cap 18 I use a cork or other yieldable washer or gasket 20 provided with a central opening of approximately the same size as the opening 11, so as to receive and clear the terminal. Beneath the gasket 20 there is a tubular rigid insulation block 21 which surrounds the terminal and is spaced therefrom likewise with a clearance which may be about the same as that between the terminal and the casing in the opening 11. This space is illustrated in Fig. 2 at 22. Below the block 21, which is preferably of porcelain, there is another gasket 23, which may be of the same size and thickness as the gasket 20, and is provided with a central opening of the same shape and size as that of gasket 20.

The casing 10 has formed therethrough four holes 24. In alignment with these holes there are four holes 25 through the block 21, the lower ends of the latter holes being enlarged to the same diameter as the holes 24. Gasket 23 is provided with holes 26 of the same size as holes 24, and gasket 20 is provided with holes 27 of the same size as the upper portions of holes 25. A fiber or other insulating tube 28 fits loosely within the holes 24 and 26 and the large part of the holes 25, and a shorter tube 29 of similar material surrounds tube 28 below or within the casing 10. The cap 18 is secured to the casing 10 by means of bolts or machine screws 30 that extend upwardly from within the casing through washers 31, through tube 28, through the smaller diameter part of hole 25, through hole 27 in gasket 20, into threaded relation with cap 18. It will be understood that there are four of these bolts or screws as illustrated herein, but that a greater or lesser number may be employed if desired. These fastenings are made of non-ferrous, non-magnetic material, such as bronze. It will be noted that they do not extend through cap 18, and hence no moisture is admitted there. When these fastenings are drawn up tightly, the cap is firmly attached to the casing, but because of the yieldability of the gaskets 20 and 23, the various parts of the mounting, particularly the por-

celain block 21, are cushioned against shock. The gaskets 20 and 23 serve to prevent any admission of moisture from the outside of the mounting and any loss of transformer oil from the interior of the transformer.

When the cap 18 is bolted down to the casing 10 in the manner described, there is no possibility of the terminal contacting either the rigid insulating material of block 21, or the walls of opening 11 in the casing, because the weld 19 and the fit of the terminal in the cap hold the terminal in relatively fixed position. On this account contraction and expansion of the terminal sets up no strains or stresses in the insulation. Any external stresses which may be communicated to the block 21, as by blows or shocks upon the cap 18 or bus bars 12, 13, will be in compression, and since porcelain has a high compressive strength, it is well adapted to take such shocks. However, even these shocks will be cushioned by the gaskets 20 and 23. Since the hole 25 in block 21 is larger than the shank of screw 30, and since the tube 28 loosely engages the shank of the screw and is in turn loosely mounted in hole 24, expansion and contraction either of the cap 18 or of the casing 10 will not transmit to the block 21 any force which might tend to cause disintegration of the latter.

Variations from the described structure may be employed. Accordingly, I desire it to be understood that the scope of the invention is to be regarded as being defined exclusively by the appended claims rather than by the foregoing description or the accompanying illustration.

Having thus described my invention, I claim:

1. In a terminal mounting for a transformer casing, a terminal, a cap adapted to be arranged outside the casing through which the terminal extends and to which it is tightly fitted, a tubular insulation block surrounding but spaced from the terminal and disposed inwardly of the cap and outwardly of the casing, an insulation gasket surrounding the terminal adjacent the said block, fastening means arranged to extend through said casing, through said gasket and block and into a downwardly opening socket in said cap for hold-

ing the parts together and securing the mounting to the casing, and insulation arranged to prevent the grounding of said cap through said fastening means.

2. In a terminal mounting, a terminal, a metal cap through which the terminal extends and to which it is secured, said cap being adapted to stand above a casing with which the mounting is employed, a tubular insulation block surrounding but not touching the terminal and disposed beneath the cap and above the casing, a plurality of screws for attachment to the casing adapted to extend loosely therethrough and through openings in the insulation block and anchored in downwardly opening sockets in the said cap, and insulation between said screws and the casing.

3. In a terminal mounting, a terminal, a metal cap through which the terminal extends and to which it is secured, two spaced yieldable insulation gaskets surrounding the terminal inwardly of said cap, a rigid block of insulation material surrounding the terminal between said gaskets but spaced away from the terminal, fastening means for attaching the cap, block and gaskets to a supporting member externally thereof comprising an elongated element extending through the supporting member, through both gaskets and said block and threaded into a downwardly opening socket in said cap, and insulation means arranged to prevent the grounding of said cap through said fastening means.

4. In a terminal mounting for a transformer casing having an opening therethrough, a terminal of smaller cross-section than said opening adapted to extend through the opening into the casing without touching the latter, a tubular insulation block surrounding the terminal outwardly of the casing spaced away from the terminal, a metal cap fitted tightly to the terminal outwardly of said block, fastenings extending through the casing and block and into a downwardly opening socket in said cap, said block serving as a spacer between said cap and said casing, and insulation means arranged to prevent the grounding of said cap through said fastenings.

LEALDAS W. HAIG.
